UNITED STATES PATENT OFFICE.

JOHN H. STILLWAGGON, OF RICHMOND HILL, NEW YORK.

FASTENER.

988,743.

Specification of Letters Patent.

Patented Apr. 4, 1911.

Application filed December 24, 1910. Serial No. 599,221.

To all whom it may concern:

Be it known that I, JOHN H. STILLWAGGON, a citizen of the United States, residing at Richmond Hill, in the county of Queens 5 and State of New York, have invented certain new and useful Improvements in Fasteners, of which the following is a specification.

This invention relates to fasteners adapted to be used with hollow metal bodies inaccessible from the rear. Its novelty consists in the construction and adaptation of the parts, and it has for its object the production of a fastener which shall be both 15 cheap to construct and efficient in use.

In the drawings, Figure 1 represents a portion of the front wall of a hollow metal body, for instance, a hollow metal partition inaccessible from the rear. Fig. 2 is a side 20 elevation of a fastener embodying my invention without an axial stub. Fig. 3 is a side elevation of the same with an axial stub. Fig. 4 is a perspective of the forms shown in Figs. 2 and 3. Figs. 4^a and 4^b are 25 respectively detail views of the split spiral disk and the axial body. Fig. 5 is a sectional view through the wall and a side view of the form of fastener shown in Fig. 3 inserted therein with a depending bracket secured thereto by a nut. Fig. 6 is a detail 30 of the nut shown in Fig. 5. Fig. 7 is a form of fastener embodying a bracket which is also used as a rotating member. Fig. 8 is a section of the wall and a side view of the 35 fastener shown in Fig. 7 inserted therein, the fastener being provided with an axial stub. Fig. 9 is a detail of a form of nut adapted to be used with the form of fastener shown in Figs. 2, 3 and 4 and provided with 40 a ring or eye, and Fig. 10 is a detail of a socket wrench adapted to be used with the form of fastener shown in Figs. 2, 3 and 4, whereby the fastener may be rotated.

In the drawings 10 designates a wall of 45 a hollow article inaccessible from the rear. For use with my improved form of fastener it must be slit as at 11 with one edge of the slit at 12 bent slightly outward or the other edge of the slit 13 bent slightly inward to 50 engage the split spiral disk of the fastener as hereinafter described. Or it may be furnished with a key hole slot in which 14 represents the round hole and 15 the longitudinal slit with separated edges 16 and 17.

55 The fastener proper comprises an axial

body 20 which is preferably provided with threads 21 in the simpler forms of the device. It is reduced at 22 to form an axial stub and a shoulder 23 is formed on the body 20 where such reduction takes place. 60 On the stub 22 there is placed a split spiral disk 24 having edges 25 and 26 bent away from each other at opposite ends of the spiral. The stub may be flush with the inner surface of the disk 24 or it may have 65 a projection 220 beyond the same (see Fig. 3). Where no means are otherwise provided for rotating the fastener it is preferably provided with a polygonal tail 27 which may be engaged by a simple form of socket 70 wrench illustrated in Fig. 10 and provided with a socket 28 adapted to engage the polygonal tail 27.

The device as described is readily secured 75 to the wall. The outermost leaf 26 of the fastener is inserted under the upturned edge 12 of the slit 11 and the fastener then being rotated, the split spiral disk is thus forced from the outside to the inside of the wall 10 as shown in Fig. 5. It will be observed that 80 the distance between the outermost leaf 25 of the spiral disk 24 and the inner shoulder 22 must be substantially equal to the thickness of the metal of which the wall 10 is composed or the fastener will not be tightly 85 secured in position and will be more or less free to rotate which is undesirable.

When the form of fastener shown in 90 Fig. 3 is used and it is provided with an inwardly extending stub 220, the key slot must be made in the wall. The stub 220 then engages the round portion 14 of such slot and the fastener is thus registered in 95 position and its manipulation is slightly easier.

After the fastener is in position a bracket member indicated at 30 may be slipped over the body 20 and held in position by a nut 31 or an internally threaded sleeve 32 having a depending ring 33 may be used, or a 100 variety of similar holding devices may be employed all of which must of necessity be provided with means for engaging the body of the fastener. I may, however, make the fastener to comprise within itself both 105 means whereby it may be rotated to position and may be adapted to support articles as a bracket after such rotation. Such a device is shown in Figs. 7 and 8, in which 20 is the body having the stub 22 and disk 110

24 as before, but in which 200 is a bracket member by means of which the device may readily be rotated.

What I claim as new is:—

- 5 1. A fastener adapted to be used in securing articles to a hollow metal wall inaccessible from the rear comprising an axial body, a split spiral disk arranged substantially at a right angle thereto and a shoulder 10 adapted to contact with the outer surface of the metal wall when the fastener is in place.
- 15 2. A fastener adapted to be used in securing articles to a hollow metal wall inaccessible from the rear comprising an axial body, a split spiral disk arranged substantially at a right angle thereto, a stub 20 arranged forward of the disk, and a shoulder adapted to contact with the outer surface of the metal wall when the fastener is in place.
- 25 3. A fastener adapted to be used in securing articles to a hollow metal wall inaccessible from the rear comprising an axial body, a split spiral disk arranged substantially at a right angle thereto and a shoulder 30 arranged at a distance from the rear of the stud substantially equal to the width of the metal plate into which the fastener is to be inserted.
- 35 4. The combination with a hollow metal article inaccessible from the rear and provided with a slit in its front face, of a fastener comprising an axial body, a split spiral disk mounted thereon and adapted to engage the said slit, and a shoulder adapted to contact with the front face of the metal article after the fastener is inserted.
- 40 5. The combination with a hollow metal article inaccessible from the rear and provided with a slit in its front face, of a fastener comprising an axial body, a split spiral disk mounted thereon and adapted to engage the said slit, and a shoulder adapted to contact with the front face of the metal article after the fastener is inserted arranged at a distance from the rear of the stud substantially equal to the width of the metal plate into which the fastener is to be inserted.
- 45 6. The combination with a hollow metal article inaccessible from the rear and provided with a key slot in its front face, a split spiral disk mounted thereon and a stub forward of the disk adapted to be inserted 50 in the round portion of the slot whereby when the fastener is rotated the split disk will engage the longitudinal portion of the slot.
- 60 7. The combination with a hollow metal article inaccessible from the rear and provided with a key slot in its front face, a split spiral disk mounted thereon and a stub forward of the disk adapted to be inserted 65 in the round portion of the slot whereby when the fastener is rotated the split disk

will engage the longitudinal portion of the slot and a shoulder adapted to contact with the front face of the metal article after the fastener is inserted.

8. The combination with a hollow metal article inaccessible from the rear and provided with a key slot in its front face, a split spiral disk mounted thereon and a stub forward of the disk adapted to be inserted in the round portion of the slot whereby when the fastener is rotated the split disk will engage the longitudinal portion of the slot, and a shoulder arranged at a distance from the rear of the stud, substantially equal to the width of the metal plate into which the fastener is to be inserted.

9. A fastener adapted to be used in securing articles to a hollow metal wall inaccessible from the rear comprising an axial body, a split spiral disk arranged substantially at a right angle thereto and a shoulder adapted to contact with the outer surface of the metal wall when the fastener is in place with means integral therewith for rotating the fastener as a whole.

10. The combination with a hollow metal article inaccessible from the rear and provided with a slit in its front face, of a fastener comprising an axial body, a split spiral disk mounted thereon and adapted to engage the said slit, and a shoulder adapted to contact with the front face of the metal article after the fastener is inserted and means for rotating the fastener to position.

11. The combination with a hollow metal article inaccessible from the rear and provided with a slit in its front face, of a fastener comprising an axial body, a split spiral disk mounted thereon and adapted to engage the said slit, and a shoulder adapted to contact with the front face of the metal article after the fastener is inserted arranged at a distance from the rear of the stud substantially equal to the width of the metal plate into which the fastener is to be inserted and means for rotating the fastener to position.

12. The combination with a hollow metal article inaccessible from the rear and provided with a key slot in its front face, a split spiral disk mounted thereon and a stub forward of the disk adapted to be inserted in the round portion of the slot whereby when the fastener is rotated the split disk will engage the longitudinal portion of the slot and means for rotating the fastener to position.

13. The combination with a hollow metal article inaccessible from the rear and provided with a key slot in its front face, a split spiral disk mounted thereon and a stub forward of the disk adapted to be inserted in the round portion of the slot whereby when the fastener is rotated the split disk will engage the longitudinal portion of the slot and a shoulder adapted to contact with

the front face of the metal article after the fastener is inserted and means for rotating the fastener to position.

14. The combination with a hollow metal article inaccessible from the rear and provided with a key slot in its front face, a split spiral disk mounted thereon and a stub forward of the disk adapted to be inserted in the round portion of the slot whereby 5 when the fastener is rotated the split disk will engage the longitudinal portion of the slot, and a shoulder arranged at a distance from the rear of the stud, substantially equal to the width of the metal plate into which 10 the fastener is to be inserted and means for rotating the fastener to position.

15. The combination with a hollow metal article inaccessible from the rear and provided with a slit in its front face, of a 20 fastener comprising an axial body, a split spiral disk mounted thereon and adapted to engage the said slit, and a shoulder adapted to contact with the front face of the metal article after the fastener is inserted and 25 means for rotating the fastener to position and securing articles thereto.

16. The combination with a hollow metal article inaccessible from the rear and provided with a slit in its front face, of a 30 fastener comprising an axial body, a split spiral disk mounted thereon and adapted to engage the said slit, and a shoulder adapted to contact with the front face of the metal article after the fastener is inserted arranged at a distance from the rear of the 35 stud substantially equal to the width of the metal plate into which the fastener is to be inserted and means for rotating the fastener to position and securing articles thereto.

40 17. The combination with a hollow metal article inaccessible from the rear and pro-

vided with a key slot in its front face, a split spiral disk mounted thereon and a stub forward of the disk adapted to be inserted in the round portion of the slot whereby 45 when the fastener is rotated the split disk will engage the longitudinal portion of the slot and means for rotating the fastener to position and securing articles thereto.

18. The combination with a hollow metal article inaccessible from the rear and provided with a key slot in its front face, a split spiral disk mounted thereon and a stub forward of the disk adapted to be inserted in the round portion of the slot whereby 55 when the fastener is rotated the split disk will engage the longitudinal portion of the slot and a shoulder adapted to contact with the front face of the metal article after the fastener is inserted and means for rotating 60 the fastener to position and securing articles thereto.

19. The combination with a hollow metal article inaccessible from the rear and provided with a key slot in its front face, a 65 split spiral disk mounted thereon and a stub forward of the disk adapted to be inserted in the round portion of the slot whereby when the fastener is rotated the split disk will engage the longitudinal portion of the 70 slot, and a shoulder arranged at a distance from the rear of the stud, substantially equal to the width of the metal plate into which the fastener is to be inserted and means for rotating the fastener to position and securing 75 articles thereto.

In testimony whereof I have affixed my signature in presence of two witnesses.

JOHN H. STILLWAGGON.
